CLAIM

The ornamental design for a strap clip, as shown and described.

DESCRIPTION

FIG. 1 is a front perspective view of a strap clip showing our new design;

FIG. 2 is a left end elevational view thereof;

FIG. 3 is an enlarged top plan view thereof;

FIG. 4 is an enlarged side elevational view thereof, the opposite side is a mirror image;

FIG. 5 is an enlarged bottom plan view thereof; and,

FIG. 6 is a right end elevational view thereof.

The strap in FIGS. 3, 4, and 5 is broken away for purposes of illustration.
